ELECTRIC CIRCUIT BREAKER

Lawrence L. Mankoff, Drexel Hill, and August L. Streeter, Broomall, Pa., assignors to General Electric Company, a corporation of New York

Filed June 4, 1958, Ser. No. 739,760
16 Claims. (Cl. 200—150)

This invention relates to an electric circuit breaker of the type in which a circuit-interrupting arc is established within a body of insulating liquid and, more particularly, relates to means for improving the dielectric strength of the insulating liquid immediately following a circuit-interrupting operation.

When a circuit-interrupting arc is established within a body of insulating liquid such as oil, the arc reacts with the oil to generate a rapidly expanding gaseous bubble. The rapid expansion of this bubble produces an abrupt increase in the pressure of the surrounding liquid. This pressure increase continues until the arc has been extinguished, at which time the pressure of both the bubble and the liquid begins to drop. Tests have shown that, for high current interruptions, this pressure drop continues until the pressure of liquid and the bubble has fallen to a very low value substantially below atmospheric pressure. The pressure remains at approximately this negative value for several cycles or more, after which it increases to a second peak, and thereafter continues to oscillate, though to a lesser extent.

During the time that the pressure is below atmospheric, the dielectric strength of the insulating medium is at an undesirably low level. There are a number of factors contributing to this low dielectric strength. One factor is that the dielectric strength of a gas falls as its pressure drops. Another factor is that the reduced pressure allows the gas bubble to rapidly grow in physical size thereby decreasing the thickness of insulating liquid which is available to suppress breakdown. Still another factor is that the extreme low pressure causes gases that are ordinarily dissolved in the liquid oil to be rapidly evolved, thus converting a portion of the liquid into a sort of foam. This foam has a substantially lower dielectric strength than clean oil. Thus, during this interval of negative pressure, the insulating medium, with its dielectric strength impaired, is much less capable of suppressing incipient flashovers, and accordingly, there is a much greater tendency for a destructive breakdown to occur through the insulating medium.

An object of the present invention is to provide for substantially increased minimum pressures during the critical low pressure interval, thereby substantially increasing the dielectric strength of the insulating medium during this interval.

Another object is to attain this result by means which does not objectionably increase the peak positive pressures developed within the breaker during any arcing condition to which it might be subjected.

In carrying out our invention in one form, we provide a circuit breaker comprising a tank of substantially fixed volume partially filled with insulating liquid and the remainder with a gas disposed above the liquid. Beneath the liquid level there is provided circuit interrupting means which acts during a circuit interruption to generate within said liquid a quantity of gases varying directly in accordance with the arcing energy developed during interruption. Also disposed beneath the liquid level is passage means affording communication between the gas above the liquid and the region in which the arcing gases are generated, the passage means having in its region of minimum cross section a predetermined total effective area. Lining the internal walls of the tank is cushioning means which has an effective surface

2

area contacting the liquid at least several times as large as said total effective area of the passage means. The cushioning means has an available-compression volume in the range of 0.3 to 4 times the maximum quantity of gases generated during the interruption of maximum rated interrupting current for the breaker. This volume of generated gases is assumed to be measured at atmospheric pressure, assuming an adiabatic expansion to atmospheric pressure.

For a better understanding of our invention, reference may be had to the following description taken in connection with the accompanying drawing, wherein:

FIG. 1 is a front elevational view partly in section of an oil circuit breaker embodying our invention.

FIG. 2 is a sectional view taken along the line 2—2 of FIG. 1.

FIG. 3 is a graph illustrating the pressures developed within the tank of FIGS. 1 and 2 during the interruption of certain heavy currents.

FIG. 4 is a graph illustrating the manner in which cushions of various size affect certain minimum pressure relationships within the tank.

FIG. 5 is an enlarged sectional view taken along the line 5—5 of FIG. 1.

Referring now to FIGS. 1 and 2, the circuit breaker shown therein comprises a metallic tank 10 comprising a body 11 of generally ellipsoidal form and a pair of spaced-apart cylindrical bushing pockets 12 projecting divergently from the top of the tank body 11. Supported within the pockets 12 by means of annular end covers 13 suitably secured to the pockets are a pair of conventional high voltage terminal bushings 14 and 15. At the inner ends of these bushings, circuit interrupters 16 of a conventional form are mounted. Each of these interrupters contains suitable separable contacts (not shown), which are electrically interconnected in series circuit relationship by means of a conductive crossbar 18 when the breaker is in its closed circuit position of FIG. 1. Since the details of the interrupters form no part of the present invention, they may assume any suitable conventional form, such as is disclosed, for example, in U.S. Patent No. 2,749,412, McBride et al., assigned to the assignee of the present invention. The contacts within the interrupters are connected to power lines 19 and 20 at the top of the breaker by the usual conductive studs extending through the centers of the terminal bushings.

Control of the multi-break circuit through the breaker is effected by lowering and raising the cross bar 18 by means of a vertically-movable operating rod 21. This operating rod 21 is connected to a suitable operating mechanism 22 mounted within an enclosure 23 at the top of the tank 10. Actuation of the mechanism 22 is effected by means of a suitable link 24 extending into the enclosure 23 through an opening sealed by suitable means (not shown). The mechanism 22 is shown in simplified form as comprising a bell-crank 26 pivoted at 27 and having its arms respectively coupled to the link 24 and the operating rod 21. The mechanism enclosure 23 is spaced from the upper periphery of the tank body 11 by means of a vertically extending pipe 25, which is shown closely surrounding the operating rod 21. The pipe 25 is suitably joined at its opposite ends to the enclosure 23 in the tank body 11, respectively.

The bushing pockets 12 and the mechanism enclosure 23 are all vented to the surrounding atmosphere at their upper ends by means of a suitable vent 30 located at the top of the enclosure 23. Conduits 33 and 34 interconnect the interiors of the bushing pocket 12 and the enclosure 23 so as to afford communication between the upper ends of the bushing pockets and the vent 30.

The tank 10 contains an arc-extinguishing insulating liquid such as oil. At all times when the breaker is to be

operated, the oil within the tank is maintained at a level which is disposed above the uppermost periphery of the tank body 11 and within the bushing pockets 12. The oil does not, however, completely fill the tank 10 and, accordingly, a body of air normally at atmospheric pressure is contained above the oil.

When the circuit breaker is tripped open from the closed position of FIG. 1, the cross bar 18 moves rapidly downward and causes each pair of contacts within the interrupters to separate and establish an arc. Each of these arcs reacts with the surrounding oil to establish a rapidly-expanding gaseous bubble. This rapid expansion of the bubble produces an abrupt increase in the pressure of the surrounding liquid, and this increase continues until the arc has been extinguished. When this occurs, the pressure of both the bubble and the liquid begins to drop, and this drop continues until the pressure reaches a minimum value where it generally remains for several cycles or more. A typical manner in which the pressure of the liquid first rises and then falls is illustrated in FIG. 3, in which curve A is a graph illustrating the pressure of the liquid within the tank during and following a typical high current circuit interruption. The values of pressure depicted are representative of those encountered with a tank such as 10, but without the cushioning means of our invention. For such a tank without the cushioning means, the pressure of the gas bubble corresponds to and is substantially equal to that of the liquid. Accordingly, curve A also depicts the bubble pressure for a tank such as 10 without the cushioning means. As will be apparent from FIG. 3, the low pressure interval is followed by another rise in pressure, this time to a second peak which is lower than the first peak. The pressure then falls and continues to oscillate, though to a progressively lesser extent.

Both the maximum pressure reached and the minimum pressure reached are dependent upon the amount of arcing gases generated, which, in turn, is dependent upon the amount of energy liberated by the arc before its extinction. For low current interruptions, where the arcing energy is relatively low, the volume of gases generated is correspondingly low and as a result the maximum pressures reached are relatively low and the minimum pressures reached are relatively high. For high current interruptions, however, much larger quantities of gases are generated, and this causes the positive peak pressures to be much higher and the minimum pressures to be much lower. For example, for extreme high current interruptions, tests have shown that, for conventional tanks (e.g., the tank 10 without the cushioning means of our invention), the pressure of the oil during the first negative swing can fall to values as low as about 11 or 12 p.s.i. below atmospheric.

Extreme low pressures, such as those developed as a result of high current interruptions, can very seriously reduce the dielectric strength of the insulating medium during the low pressure interval. This can lead to destructive flashovers through the insulating medium, for example, from the high voltage interrupter to the grounded tank, during this low pressure interval.

There are several factors which are believed to be responsible for the low dielectric strength during the low pressure interval. One is that the dielectric strength of the gas decreases as its pressure decreases, with the result being that the dielectric strength of the gas within the bubble decreases as its pressure falls. Another factor is that the reduced liquid pressure allows the bubble to rapidly grow in size thereby decreasing the thickness of the insulating liquid which is available to suppress breakdown, e.g., the liquid between the bubble and the tank wall. Still another factor is that the extreme low pressure causes gases that are ordinarily dissolved in the liquid oil to be rapidly evolved, thus converting a portion of the liquid into a sort of foam having a substantially lower dielectric strength than clean oil.

Studies made of the above-described pressure oscillations indicate that the negative pressure swing results from the kinetic energy of the oil displaced into the air chamber at the top of the tank by the gaseous arc-generated bubbles. The oil, in moving away from the rapidly-expanding bubbles, attains substantial kinetic energy, especially during high current interruptions. The body of air at the top of the tank tends to oppose this upward movement of the oil mass, but since the body of air is relatively large and is vented to atmosphere, it can exert only minor opposition to the moving oil mass. As a result, the oil mass keeps moving, even after the arc is extinguished, thus allowing the gas bubbles to continue expanding. This continued expansion when no arcing gases are being generated lowers the pressure of both the bubbles and the surrounding liquid to the objectionably low values described hereinabove. Finally the bubble pressure becomes low enough to enable the atmospheric pressure at the top of the tank to stop the oil mass and to start it moving back toward the low pressure bubbles. Once the mass of oil becomes accelerated in reverse toward the gas bubble it overshoots equilibrium pressure, giving rise to the second pressure peak previously mentioned.

Constructing the circuit breaker in accordance with the present invention has resulted in very materially increasing the minimum pressures developed during the above described low pressure interval. In carrying out our invention in one form, we have lined a large area 30 of the internal wall of the tank with a layer of resilient cushioning material. This layer of cushioning material is preferably in the form of a closed-cell sponge 40 made of a synthetic rubber which is highly resistant to oil deterioration, such as, for example, the synthetic rubber sold under the trademark "Buna-N." The closed cells of the sponge 40 are gas filled, preferably with nitrogen. Sponge material of this character is commercially available under the trademark "Rubatex" and is further characterized by its lack of absorbency with respect to liquids in which it is immersed.

This sponge material 40 can be attached to the tank walls in any suitable manner, but, as shown in FIGS. 2 and 5, we prefer to rely upon suitable studs 42 fixed to the tank wall and projecting through the sponge 40. Suitable strips 44 having holes therein registering with the studs 42 are disposed on the inner side of the sponge 40. These strips are clamped against the sponge by nuts 46 threaded on the studs, and thus act to secure the sponge in place against the tank wall.

When the interrupter is operated to establish circuit-interrupting arcs within the oil, the rapidly expanding gaseous bubble forces the surrounding oil primarily toward the resilient cushion 40 instead of up into the air pocket at the top of the tank. This compresses the gas within the cushion and thus causes the cushion to develop a relatively large opposing force before the pressure in the bubble can swing below atmospheric pressure. This opposing force counterbalances the forces due to the kinetic energy of the oil mass and thus very substantially raises the afore-mentioned minimum pressures resulting from this kinetic energy.

The ability of the cushion to act effectively to limit the negative pressure swings depends upon a number of important factors. For example, it is important that the internal surface area of the cushion in contact with the oil be at least several times greater than the access area to the body of air at the top of the tank. This access area is the total area of all passages leading from the region where the gas bubbles are initiated to the air chamber at the top of the tank, measured in the region where the passages have their minimum cross section. For example, in the disclosed tank this access area would be the total internal cross sectional of the two bushing pockets 12 and the pipe 25, minus the cross sectional

area of the bushings 14 and 15 and the operating rod 21, measured approximately along the line A—A.

In general, the greater the ratio of the cushion area to the access area, the greater will be the influence of the cushion in controlling the pressure peaks and the weaker will be the influence of the air chamber. This is due to the fact that increasing this ratio causes a relatively greater proportion of the oil displaced by the arcing bubbles to be moved toward the cushion rather than toward the air chamber. By having the surface area of the cushion at least several times larger than the access area, most of the oil so displaced moves toward the cushion rather than toward the air chamber, thus allowing the cushion to exert a predominating effect on the pressure peaks.

It is also important that the cushioning material have a rather limited "available-compression volume." This term, as used in this application, may be defined as that volume of the cushion which is available for compression by the arc-generated pressures. For example, with a gas-filled sponge, the available compression volume is the volume occupied by the gas in the sponge, referred to standard atmospheric pressure and temperature (i.e., about 25° C.). This available compression volume for a cushion relying upon a gas as the compressible medium should fall within a range of about 0.3 to 4 times the largest volume of gas generated by the breaker at full interrupting rating (assuming the generated-gas volume to be measured at atmospheric pressure after an adiabatic expansion to atmospheric pressure). This is illustrated in the graph of FIG. 4 which depicts on its ordinate the approximate minimum pressures that will be developed with cushions of differing available-compression volumes. The available compression volume is plotted on a logarithmic scale on the abscissa of the graph in terms of the ratio of the available compression volume to the maximum volume of gases that will be generated (referred adiabatically to atmospheric pressure). The curve is based upon tests and calculations with a tank such as depicted at 10 in the drawings, where the effective cushion area is at least several times the access area to the air pocket at the top of the tank 10 and, more particularly, in the neighborhood of ten times the access area.

Referring to the curve, the minimum pressure that will be developed when no cushion is present is indicated at the point where the curve crosses the ordinate of the graph, i.e., at about 3 p.s.i. absolute. Assume next that cushions of predetermined available-compression volumes are utilized. With a cushion having an available compression volume of about 0.3 times the maximum volume of generated gas, the bubble pressure is roughly doubled, and this produces a substantial increase in the dielectric strength of the insulating medium between the interrupter and the tank. The maximum increase in bubble pressure and, hence, in dielectric strength occurs when the available compression volume is between one and two times the maximum volume of gases generated. In this preferred range, the minimum pressure has been more than tripled and the dielectric strength of the overall insulating medium has been increased by about 50% as compared to that obtained without a cushion.

Increasing the cushion volume beyond this preferred range reduces the minimum bubble pressure, and if the plotted volume ratio exceeds a value of about four, the minimum pressure falls to appreciably less than twice that obtained without the cushion. Such relatively low minimum pressures produce correspondingly low values of dielectric strength, with the result being that the cushion is operating relatively inefficiently when of such a large volume. As an example, of such inefficiency, when the cushion volume is ten times the overall bubble volume, the minimum pressure is only about one p.s.i. higher than without the cushion, which represents only

a very slight increase in the dielectric strength of the overall insulating medium. The probable explanation for the poor results obtained with cushions of such relatively large volumes is that such cushions are capable of developing no appreciable opposing force to the outwardly moving oil mass before the pressure in the gas bubble swings to an objectionably low value.

To illustrate the manner in which the cushion 40 affects the gas bubble pressure, a curve B has been included in FIG. 3. This curve, which is based upon tests and calculations, depicts the approximate gas bubble pressures developed with a cushion 40 having (1) an available compression volume substantially equal to the largest volume of gas generated by the breaker at full interrupting rating (assuming that the generated-gas volume is referred adiabatically to atmospheric pressure) and (2) an effective area of approximately 10 times the access area leading to the air pocket at the top of tank 10. As will be apparent from curve B, the gas pressure, in falling from its peak, drops to a minimum value of about 9 p.s.i. absolute, as compared to the 3 p.s.i. absolute minimum value resulting from operation without the cushion, as is illustrated by curve A. This higher minimum pressure of curve B results in a substantially higher dielectric strength of the insulating medium in the tank during the critical interval after interruption and, hence, in much less likelihood of a breakdown to the tank.

In the above description, no mention has been made of the resilience of the walls of the tank itself. These walls yield slightly in response to the maximum pressure peaks, but in a tank of the construction shown in the drawings, this increased volume is so slight as to be practically negligible. However, for a tank which might have walls of a more yieldable nature, expansion of the tank itself becomes a more significant factor. To compensate for such tank expansion, the cushion volume should be reduced by an amount equal to the increase in tank volume resulting from tank expansion in response to an internal pressure of about 45 p.s.i. gage. For a tank of the construction shown in the drawing, tank expansion in response to such a pressure is practically negligible and, thus, the lower limit for the cushion volume, i.e., about 0.3 times the maximum volume of gases generated, remains substantially unchanged.

Since the cushion area must be large in comparison to the previously-described access area leading to the air chamber at the top of the tank, it is desirable that this access area be relatively small in order to hold the cushion area within practical limits. There is, however, a certain minimum value, above which this access area should be maintained. In this regard, it sometimes happens that an arc develops between the interrupter and the tank, say as a result of a lightning striking the breaker or connected power line. Opening of the breaker itself might have no effect on such an arc, and to terminate such an arc, it is usually necessary that one or more back-up circuit breakers be opened. This usually requires at least five or more cycles, i.e., $\frac{1}{42}$ of a second or more, and during this relatively prolonged interval the tank must be capable of safely accommodating the gases that would be generated by such arcing. To meet this requirement, the access area leading to the air pocket should be large enough to allow the liquid displaced by arcing gases under such circumstances to flow into the air pocket at a rate sufficiently high to prevent damaging pressures from developing within the tank. The volume of the air pocket and the size of its vent also must be large enough to allow the tank to safely accommodate the liquid displaced under such circumstances. In the disclosed tank, for example, we prefer that the air pocket be about 30 times the maximum volume of gases that would be generated by the breaker at its full interrupting rating (referring this volume adiabatically to atmospheric pressure). The vent preferably should be at least

several inches in diameter, it being understood that enlarging the vent allows certain reactions to be made in the volume of the air pocket. Thus, the access area and the air pocket should be large enough to hold to a safe level the maximum pressure that will be developed within the tank during $\frac{1}{12}$ of a second of arcing to tank. A value of 80 p.s.i. gage is a practical upper limit for the maximum pressure permissible under this latter condition.

Constructing the cushioning means from a closed-cell sponge is especially advantageous for a number of reasons. First of all, the gas entrapped within the sponge is completely isolated from the oil and therefore is not subject to being absorbed by the oil, as is the case in cushions where gas-to-oil contact is present. In addition, the sponge is much more resistant to mechanical damage than most other types of cushions, e.g., bladders and the like, inasmuch as a puncture results in only an insignificant loss of entrapped gas from the sponge. The sponge-type of cushion is also advantageous in being readily adaptable to tanks of varying sizes and shapes and in providing a relatively large surface area per unit of volume.

While a circuit breaker tank of the general configuration shown in the drawing is especially well suited to the practice of the present invention, it is to be understood that the invention is also applicable, at least in its broader aspects, to tanks of other configuration.

It will be apparent to those skilled in the art that various other modifications may be made without departing from the invention in its broader aspects, and we, therefore, intend in the appended claims to cover all such changes and modifications as fall within the true spirit and scope of the our invention.

What we claim as new and desire to secure by Letters Patent of the United States is:

1. An electric circuit breaker comprising a metallic tank, a body of insulating liquid partially filling said tank and a body of gas normally at approximately atmospheric pressure within said tank disposed above said liquid, circuit-interrupting means acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said cushioning means having an available-compression volume generally in the range of one to two times said predetermined volume minus the increased available volume resulting from tank expansion in response to an internal pressure of about 45 p.s.i. gage.

2. An electric circuit breaker comprising a metallic tank, a body of insulating liquid partially filling said tank and a body of gas normally at approximately atmospheric pressure within said tank disposed above said liquid, circuit-interrupting means acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least

several times as large as said total effective area of said passage means, the maximum quantity of gases generated by said interdrupting means during interruption of any currents within the interrupting rating of the breaker having a predetermined volume measured at atmospheric pressure, assuming an adiabatic expansion to atmospheric pressure, said cushioning means having an available-compression volume in the range of about 0.3 to 4 times said predetermined volume minus the increased available volume resulting from tank expansion in response to an internal pressure of about 45 p.s.i. gage.

3. The circuit breaker of claim 1 in which said access area is sufficiently large and said body of gas is of sufficiently large volume to allow an arc of maximum rated current to be maintained to the tank for a period of at least $\frac{1}{12}$ second without developing pressure sufficient to damage the circuit breaker.

4. The circuit breaker of claim 2 in which said access area is sufficiently large and said body of gas is of sufficiently large volume to allow an arc of maximum rated current to be maintained to the tank for a period of at least $\frac{1}{12}$ second without developing pressure sufficient to damage the circuit breaker.

5. An electric circuit breaker comprising a metallic tank, a body of insulating liquid partially filling said tank and a body of gas normally at approximately atmospheric pressure within said tank disposed above said liquid, circuit-interrupting means acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said cushioning means having an available-compression volume generally in the range of one to two times said predetermined volume minus the increased available volume resulting from tank expansion in response to an internal pressure of about 45 p.s.i. gage, said cushioning means comprising sponge material lining the internal walls of said tank, said sponge material being of a closed-cell, gas-filled cell construction.

6. An electric circuit breaker comprising a metallic tank, a body of insulating liquid partially filling said tank and a body of gas normally at approximately atmospheric pressure within said tank disposed above said liquid, circuit-interrupting means acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure, assuming an adiabatic expansion to atmospheric pressure, said cushioning means having an available-compression volume in the range of about 0.3

to 4 times said predetermined volume minus the increased available volume resulting from tank expansion in response to an internal pressure of about 45 p.s.i. gage, said cushioning means comprising sponge material lining the internal walls of said tank, said sponge material being of a closed-cell, gas-filled cell construction.

7. In an electric circuit breaker, a metallic tank comprising a body portion of generally ellipsoidal configuration and a pair of tubular bushing pockets projecting outwardly from the upper part of the said body portion, a body of insulating liquid filling said tank to a minimum level disposed within said bushing pockets and a body of gas normally at approximately atmospheric pressure disposed within said tank above said liquid, terminal bushings extending through said pockets into said tank body, circuit-interrupting means located at the inner end of said terminal bushings and acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said cushioning means having an available-compression volume generally in the range of one to two times said predetermined volume minus the increased available volume resulting from tank expansion in response to an internal pressure of about 45 p.s.i. gage.

8. In an electric circuit breaker, a metallic tank comprising a body portion of generally ellipsoidal configuration and a pair of tubular bushing pockets projecting outwardly from the upper part of the said body portion, a body of insulating liquid filling said tank to a minimum level disposed within said bushing pockets and a body of gas normally at approximately atmospheric pressure disposed within said tank above said liquid, terminal bushings extending through said pockets into said tank body, circuit-interrupting means located at the inner end of said terminal bushings and acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said cushioning means having an available-compression volume generally in the range of 0.3 to 4 times said predetermined volume minus increased available volume resulting from tank expansion in response to an internal pressure of about 45 p.s.i. gage.

9. In an electric circuit breaker, a metallic tank, a pair of terminal bushings projecting into said tank at the upper end of said tank, said tank comprising a lower portion generally semi-ellipsoidal in shape and an upper portion supporting said terminal bushing, a body of insulat-

ing liquid filling said tank to a level above the inner ends of said bushings and a body of gas normally at approximately atmospheric pressure disposed within said tank above said liquid, circuit interrupting means at the inner ends of said bushings acting during a circuit-interrupting operation to generate within said liquid a quantity of gases varying directly in accordance with the arcing energy developed during interruption, means extending into the vicinity of said bushings and defining beneath the level of said liquid restricted passage means affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said cushioning means having an available-compression volume generally in the range of one to two times said predetermined volume minus the increased available volume resulting from tank expansion in response to an internal pressure of about 45 p.s.i. gage.

10. In an electric circuit breaker, a metallic tank, a pair of terminal bushings projecting into said tank at the upper end of said tank, said tank comprising a lower portion generally semi-ellipsoidal in shape and an upper portion supporting said terminal bushings, a body of insulating liquid filling said tank to a level above the inner ends of said bushings and a body of gas normally at approximately atmospheric pressure disposed within said tank above said liquid, circuit interrupting means at the inner ends of said bushings acting during a circuit-interrupting operation to generate within said liquid a quantity of gases varying directly in accordance with the arcing energy developed during interruption, means extending into the vicinity of said bushings and defining beneath the level of said liquid restricted passage means affording communication between the gas disposed above said liquid and the region in which said arcing gases are generated, said passage means having in its region of minimum cross-section a predetermined total effective area, cushioning means lining the internal walls of said tank and having an effective surface area contacting said liquid at least several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said cushioning means having an available-compression volume generally in the range of 0.3 to 4 times said predetermined volume minus the increased available volume resulting from tank expansion in response to an internal pressure of about 45 p.s.i. gage.

11. An electric circuit breaker comprising a metallic tank of substantially constant volume, a body of insulating liquid partially filling said tank and a body of gas normally at approximately atmospheric pressure within said tank disposed above said liquid, circuit-interrupting means acting during a circuit interruption to generate within said liquid a quantity of gases varying directly in accordance with the arcing energy developed during interruption, passage means disposed beneath the level of said liquid and affording communication between the gas disposed above said liquid and the region in which said arcing gases are generated, said passage means having in its region of minimum cross-section a predetermined total effective area, cushioning means formed of sponge material lining the internal walls of said tank and having an effective surface area contacting said liquid at least

several times as large as said total effective area of said passage means, the maximum quantity of gases generated by said interrupting means during interruption of any currents within the interrupting rating of the breaker having a predetermined volume measured at atmospheric pressure assuming an adiabatic expansion to atmospheric pressure, said sponge material comprising closed-cells filled with gas, the total volume of gas in said cells measured at standard atmospheric pressure and temperature being in the range of about 0.3 to 4 times said predetermined volume.

12. The circuit breaker of claim 11 in which the total volume of gas in said closed cells, measured at standard atmospheric pressure and temperature, is in the range of one to two times said predetermined volume.

13. An electric circuit breaker comprising a tank containing insulating liquid, an interrupter disposed within said tank and insulated therefrom, said interrupter containing insulating liquid, means for establishing a circuit-interrupting arc within the insulating liquid of the interrupter to generate a gaseous bubble outside of the interrupter within said tank, means for controlling the internal pressures within said tank produced by said bubble comprising a resilient sponge lining the internal walls of said tank and disposed in contact with said liquid, said sponge being of a closed-cell construction with its cells being filled with entrapped gas.

5

14. The circuit breaker of claim 1 in which said cushioning means has an effective surface area contacting said liquid at least in the neighborhood of ten times as large as said total effective area of said passage means.

15. The circuit breaker of claim 2 in which said cushioning means has an effective surface area contacting said liquid at least in the neighborhood of ten times as large as said total effective area of said passage means.

16. The circuit breaker of claim 6 in which said cushioning means has an effective surface area contacting said liquid at least in the neighborhood of ten times as large as said total effective area of said passage means.
